(57) **CLAIM**

I claim the design for a drop in sink, as shown and described.

DESCRIPTION

FIG. 1 is a top left front perspective view of a drop in sink of my design;

FIG. 2 is a top view thereof, the bottom view being plain, unornamented and unclaimed;

FIG. 3 is a front elevational view thereof, the rear elevational view being identical;

FIG. 4 is a right side elevational view thereof, the left side elevational view being identical; and,

FIG. 5 is a sectional view taken along line 5-5 in FIG. 2, the dashed lines representing unclaimed sectional regions.
